UNITED STATES PATENT OFFICE.

ARTHUR W. WELLINGTON, OF WATERBURY, CONNECTICUT, ASSIGNOR TO THE CHASE COMPANIES, INC., OF WATERBURY, CONNECTICUT, A CORPORATION.

FLUSH-TANK FITTING.

Application filed September 4, 1926. Serial No. 133,564.

Fig. 1 is a broken plan view of my improved revoluble-handle flush-tank fitting shown as applied to the front wall of a tank;

Fig. 2 is a broken view of the fitting in inside elevation; and

Fig. 3 is a vertical sectional view of the fitting on the line 3—3 of Fig. 1.

My invention relates to a revoluble-handle flush-tank fitting, the object being to produce a simple, durable and dependable fitting of the character described, constructed with particular reference to the avoidance of dead centers, when the handle is in a vertical plane, and thus to minimize the chance of the valve-lifting lever being stalled in its elevated position, in which the valve is prevented from returning to its closed position upon its seat in the tank.

With these ends in view, my invention consists in a revoluble-handle flush-tank fitting having certain details of construction as will be hereinafter described and pointed out in the claim.

In carrying out my invention, as herein shown, the inner end of the valve-lifting lever 5 is turned downward to form an inclined lifting-arm 6, the upper edge of which provides a downwardly-inclined operating-surface 7 for co-action with the rounded face 8 of an eccentric 9 rigidly mounted upon the inner end of the handle-shaft 10 at an acute angle and in such position, relative to the handle 11 carried by the outer end thereof, that when the said handle is in its normally-depending position in the vertical plane, the plane of the eccentric is substantially parallel with the said surface, with a clearance-space 12 between them to permit a slight movement of the handle without disturbing the said lever.

Under this construction, when the said handle 11 is swung in either direction, the rounded face 8 of the eccentric 9 engages with the inclined upper edge 7 of the lifting-arm 6 of the lever, with the effect of lifting the outer end of the lever and hence the valve (not shown) from its seat in the tank.

When the user lets go of the handle, grav-

ity will return it into its normal, depending position in the vertical plane, in which the eccentric 8 is clear of the edge 7 of the arm 6 of the lever, so that the factor of dead centers, when the handle is in a vertical plane is eliminated, and, consequently, there is practically no chance of the lever being stalled in its raised position, in which the valve is not permitted to move into its closed position.

As shown, the valve-lifting lever 5 is hung upon a stud 13, carried by a bracket-arm 14 mounted upon an externally-threaded assembly-sleeve 15, which provides a bearing for the shaft 10 aforesaid, and is mounted, as usual, in the front 16 of the tank, its threaded outer end receiving a nut 17 by which a washer 18 is brought to a firm bearing upon the outer face of the front of the tank, whereby variations in the thickness of the said wall are provided for.

A lug 19, formed upon the bracket-arm 14 at a point below the stud 13 carried thereby, limits the downward movement of the outer end of the lever and hence prevents the upper edge 7 of the lifting-arm of the lever from acting as a stop, the said inclined edge of the arm being thus always held out of engagement with the eccentric 9, save when the same is operated by turning the handle 11 in one direction or the other.

I claim:

In a revoluble-handle flush-tank fitting, the combination with a valve-lifting lever, the inner end of which is provided with a downwardly-inclined operating-surface, of a handle-shaft, a handle located at the outer end thereof, and an eccentric positioned upon the inner end thereof at an acute angle with respect to the handle and so as to normally occupy a plane parallel with the said operating-surface when the handle is depending in the vertical plane, whereby the weight of the handle and eccentric act in unison to move the said eccentric from a dead-center position with respect to the said operating-surface.

In testimony whereof, I have signed this specification.

ARTHUR W. WELLINGTON.
